Primary Examiner—Charles A Rademaker*(74) Attorney, Agent, or Firm*—Ostrolenk Faber LLP**CLAIM**

The ornamental design for a platen unit for a label application device, as shown and described.

DESCRIPTION

FIG. 1 is a top perspective view of a platen unit for a label application device showing my new design;

FIG. 2 is a side view thereof, the opposite side being a mirror image;

FIG. 3 is a top view thereof; and,

FIG. 4 is a top perspective view from the opposite side.

The bottom and the rear of the platen unit are not illustrated in the drawing and form no part of the claimed design.
